Primary Examiner — Catherine S Posthauer*(74) Attorney, Agent, or Firm* — Smith & Hopen, P.A.;
 Paul Murty(57) **CLAIM**

The ornamental design for a combination bucket lid and stand, as shown and described.

DESCRIPTION

FIG. 1 is a top-side perspective view of a combination bucket lid and stand.

FIG. 2 is a bottom-side perspective view thereof.

FIG. 3 is a side elevation view thereof.

FIG. 4 is a side elevation view thereof.

FIG. 5 is a side elevation view thereof.

FIG. 6 is a side elevation view thereof.

FIG. 7 is a top plan view thereof.

FIG. 8 is a bottom plan view thereof.

FIG. 9 is a top perspective view thereof, shown in a position of use with an exemplary bucket; and,

FIG. 10 is a top perspective view thereof, shown in another position of use with an exemplary bucket.

The broken lines are shown for the purpose of illustrating both parts of the article as well as environmental subject matter. None of the broken lines form part of the claimed design.

1 Claim, 5 Drawing Sheets(56)
